AUTOMATIC CLOSING MEANS FOR ROLLER FIRE-SHUTTERS.

1,238,041.

Specification of Letters Patent. Patented Aug. 21, 1917.

Application filed May 22, 1916. Serial No. 99,202.

To all whom it may concern:

Be it known that I, WILLIAM G. MILLER, a citizen of the United States, residing at Toronto, in the county of York, Province of 5 Ontario, Canada, have invented certain new and useful Improvements in Automatic Closing Means for Roller Fire-Shutters, of which the following is a specification.

This invention relates to roller fire shutters and consists in the novel features of 10 construction and association of parts as hereinafter set forth and claimed.

The invention has for its object the provision of simple and improved means for application to fire doors or shutters carried upon rollers operated by counter-balancing springs restrained under a winding tension, wherein provision is made for associating with the counter-balancing spring within 20 the roller an auxiliary floating or idle spring, which is normally set and restrained under tension independent of said roller by locking means releasable upon a dangerous rise in temperature, and which is provided 25 with engageable gripping means for effecting a driving connection with said roller to impart movement thereto against the tension of the counterbalancing spring to start and drive said shutter downwardly and cause 30 it to close automatically in event of fire.

In the accompanying drawings, a preferred embodiment of the novel and essential features of the present invention is illustrated, and in which,

35 Figure 1 is a front elevation of a portion of a wall having a door or opening therein equipped with a shutter embodying my improved features of construction.

Fig. 2 is an end elevation of the housing 40 for the shutter containing the roller and showing the releasable locking means for restraining the auxiliary spring therein.

Fig. 3 is a central horizontal longitudinal section through the housing and roller, the 45 auxiliary spring shaft and locking disk being shown in elevation.

Fig. 4 is an enlarged longitudinal sectional detail through the end of the roller containing the auxiliary spring, the shaft 50 upon which it is anchored and the chuck or gripping head in the roller carrying a slide- able nut threaded on the shaft through which a driving connection is established between the spring and roller.

Fig. 5 is a cross-section through the roller 55 on dotted lines 3—3 of Fig. 4.

Referring to the parts by the characters of reference marked on the drawings, 1 indicates a wall having a door-way or opening 2 therein, provided on opposite sides with 60 angular guide-strips 3. Mounted on heads 4 and 5, suitably secured to the wall above the opening, is an elongated housing 6 containing a barrel or roller 7 upon which a flexible apron or shutter 8 is suitably mounted 65 (as is common, but not shown) to wind thereon and to travel with its edges in the guide-strips 3. The ends of the roller are closed by collars 9 and 10 secured therein by screws 11. (See Fig. 3.) Extending freely 70 through the collar 9, and through a hub 12 on the head 4, is a stub shaft 13, which is anchored against rotation in said hub by a pin 14 extending therethrough. Fixed on the inner end of this shaft by a pin 15 is a 75 collar 16, and embracing said collar, and anchored thereto by said pin at one end, is a coiled spring 17, the opposite end of which embraces and is connected by a pin 18 to a plug 19, which is secured within the roller 80 by screws as at 20. This spring operates upon the roller to counter-balance the weight of the shutter and is set under the required tension by rotating and locking the shaft 13 to normally retain the shutter in the 85 raised position upon the roller.

To provide means for automatically lowering the shutter when raised, in the event of fire, without requiring the release of the counter-balancing spring, or interfering 90 with its operation in normally controlling the shutter, the following mechanism is employed. (See Fig. 4.) Rotatably embraced by the end of the roller adjacent the head 5 of the housing, is a bearing sleeve 21 having 95 a shoulder 22 which engages the inner face of the collar 10, and also has a reduced extension 23 which passes freely through said collar and is fitted to and seated at its outer end in an angular aperture 24 formed in the 100 hub 25 of said head, in which it is anchored against rotation and forms a bearing on which the collar 10 rotates in carrying the end of the roller. Extending freely through the sleeve 21, and well into the corresponding end of the roller, is a shaft 26 which is held against outward axial movement by means of a pin 27 extended through the 105

shaft and engaging a washer 28 bearing on the inner end of said sleeve. The inner end of the shaft 26, which is exteriorly screw threaded as at 29, extends through and is 5 journaled to rotate in a chuck or gripping head 30 which fits closely within and is fixedly secured to the roller 7 by screws 31.

Formed in the innermost end of the chuck or head 30, and extending axially into the body thereof is an enlarged socket 32 having angular side walls which embrace the correspondingly shaped edges of a nut 33 engaged with the threads 29 of the shaft 26. Said nut is locked against rotation in 10 said head by engagement with the walls thereof but is free to travel on said threads and to slide longitudinally of said socket in permitting relative rotary movement of the shaft and roller, and interposed between the 15 nut and the end wall of the socket is a cushioning washer 34, which receives the thrust of the nut when it reaches the limit of its inward travel in said socket. The shaft 26 is held against longitudinal movement 20 through the head 30, under the drawing strain of the nut therein, by a collar 35 which is secured upon said shaft by a pin 36 to abut against the outer end of said head and receive the jamming thrust of the 25 nut, through the clamping action of which upon the head a locked driving connection in one direction is established between the shaft and roller.

Rotary driving force is exerted upon the 30 shaft 26 in a reverse direction to that exerted by the counterbalancing spring upon the roller by an auxiliary coiled spring 37 contained within the roller and which embraces at one end the collar 35 of said shaft 40 to which it is secured by the pin 36, and receives in its opposite end the inner end of the fixed sleeve 21 to which it is anchored by a pin 38. The shaft is normally releasably locked under a suitable unwinding tension 45 stored in the spring, by means of a disk 39 which is fixed by a pin 40 to the outer end of said shaft adjacent the head 5 of the housing and carries thereon a plurality of laterally projecting circumferentially spaced lugs 50 each of which has a bore 42 for the reception of a radially projecting locking pin 43. The projecting end of this pin (see Figs. 1 and 2) is normally engaged with an inclined shoulder 44 formed in the inner edge of a right angled latch lever 45, the upper end of which is pivoted to hang vertically upon a stud 46 anchored in a bearing bracket 47 projecting from the head 5 of the housing, and the lower end of this lever 60 extends inwardly horizontally of the housing and carries a weight 48 by which it is caused to swing outwardly to disengage the locking pin 43. The inward movement of the latch lever is limited by engagement with a stop lug 49 on the head of the housing, and the

lever is normally held against this stop and with its shoulder 44 engaged with the locking pin 43 by means of a cable 50 connected to said lever and to a fixed support 51, and which also embraces a soft metal link 52 fusible at a given temperature to release the locking means. The operation of the device will now be understood as follows:

The auxiliary spring being set under tension, and restrained by its shaft and the locking means therefor, will be inoperative to effect the normal operation of the roller in raising and lowering the shutter under the influence of the counterbalancing spring, for the reason that the nut 33 will be free to travel outwardly in the socket 32 and upon the threads of the shaft 26 with the rotation of the roller in lowering the shutter, and inwardly thereof with a reverse movement of the roller in raising the shutter. The lead of the threads 29 is such with respect to the number of revolutions of the roller necessary to carry the shutter the required distance, together with the depth of the socket 32 and the position of the nut therein, that an intervening space is left between the nut and cushioning washer when the shutter shall have reached the limit of its upward travel. This space permits of a slight idle travel of the nut as well as the shaft when being further drawn by the rotation of said shaft into engagement with the cushioning washer, whereby, when said shaft is released through the fusing of the link and through the resultant disengagement of the latch lever from the locking pin of the disk, it will receive the stored force of the auxiliary spring by which it will be rapidly rotated in a direction to draw and jam the nut into locking engagement with the cushioning washer, between which and the thrust collar on said shaft a driving connection will be established with the gripping head and roller. The roller will thus be abruptly started through the force of impact of the striking engagement of the nut and will be caused to rotate in a direction to lower the shutter against the tension of the counterbalancing spring, which latter spring, by reason of the increasing tension stored thereon as the shutter descends, will serve to cushion the shock as said shutter reaches the limit of its downward travel. In this position the auxiliary spring will have spent its force and the shaft will remain idle permitting the nut to ride outwardly and inwardly thereon and enabling the shutter to be further raised and lowered under the control of the counterbalancing spring.

Having thus fully set forth my invention, I claim as new and desire to secure by Letters Patent as follows:

1. In means for closing fire shutters, the combination of a roller, a shutter mounted thereon, a bearing head fixed in said roller

and having an angular axial opening therein, a nut slidably seated in said opening, a rotatable shaft extending into said roller and through said bearing head and having
5 screw threaded engagement with the nut therein, means to restrain said shaft against axial movement through said head, a coiled spring connected to said shaft and to a fixed support, releasable locking means for re-
10 straining said shaft against rotation under the tension of said spring, and means for restraining said locking means embracing a fusible member.

2. In means for closing fire shutters, the
15 combination of a hollow roller, a shutter mounted thereon, a housing containing said roller and shutter, a bearing sleeve fixed to said housing and extending into said roller, a shaft rotatably extending through said sleeve and screwthreaded at its inner end, a bearing head in said roller loosely embrac-
20 ing the threaded end of said shaft, a collar on said shaft abutting against said bearing head, a coiled spring connected with said collar and with said sleeve, a nut non-rotatably and slidably seated in said bearing head and having screw threaded engagement with said shaft, said nut being adapted to normally travel on said shaft with the rotation of said roller and to be drawn into locking engagement with said head through the rotation of said shaft in one direction, a disk fixed on said shaft and having a locking pin thereon, a latch lever releasably engaging said pin and restraining said disk and shaft
25 against rotation under the tension of said spring, and restraining means for retaining said latch lever engaged and releasable therewith upon a dangerous rise in temperature.

In testimony whereof I sign this specification.

WILLIAM G. MILLER.
